CLAIM

The ornamental design for a card with an antenna and a blue rectangle, as shown and described.

DESCRIPTION

FIG. 1 is a perspective view of a card with an antenna and a blue ornamental rectangle showing our new design;

FIG. 2 is a top plan view of the card of FIG. 1;
FIG. 3 is a bottom plan view of the card of FIG. 1;
FIG. 4 is a right side elevational view thereof;
FIG. 5 is a left side elevational view thereof;
FIG. 6 is a front elevational view thereof; and,
FIG. 7 is a rear elevational view thereof.

The broken lines showing environment in the drawings are shown for illustrative purposes only and form no part of the claimed design.
